UNITED STATES PATENT OFFICE

106,286

DESIGN FOR A HIGHWAY MARKER

Allie E. Dickson, Orlando, Fla.

Application June 14, 1937, Serial No. 69,840

Term of patent 14 years

To all whom it may concern:

Be it known that I, Allie E. Dickson, a citizen of the United States, residing at Orlando, in the county of Orange and State of Florida, have invented a new, original, and ornamental Design for a Highway Marker, of which the following is a specification, reference being had to the accompanying drawing forming part thereof.

In the accompanying drawing:

Figure 1 is a perspective view of a highway marker showing my new design;
Figure 2 is a front elevation;
Figure 3 is a side elevation; and
Figure 4 is a top plan view.

I claim:

The ornamental design for a highway marker, as shown.

ALLIE E. DICKSON.
